[57] CLAIM

The ornamental design for a dosimeter for monitoring
radiation exposure, as shown and described.

DESCRIPTION

FIG. 1 is a front elevational view of the dosimeter for
monitoring radiation exposure showing our new design;

FIG. 2 is a rear elevation view thereof;

FIG. 3 is a top plan view thereof;

FIG. 4 is a left side elevational view thereof; and

FIG. 5 is a bottom front right side perspective view

thereof.

The broken lines in FIG. 5 are a wire clamp that is

shown for illustrative purposes only.

FIG. 1

FIG. 2

FIG. 3

FIG. 4

FIG. 5
